UNITED STATES PATENT OFFICE.

JOHAN OTTO EMANUEL TROTZ, OF WORCESTER, MASSACHUSETTS.

APPARATUS FOR MAKING COMPOUND METAL INGOTS.

SPECIFICATION forming part of Letters Patent No. 639,005, dated December 12, 1899.

Application filed July 2, 1898. Serial No. 685,075. (No model.)

To all whom it may concern:

Be it known that I, JOHAN OTTO EMANUEL TROTZ, of the city and county of Worcester and State of Massachusetts, have invented 5 certain new and useful Improvements in Apparatus for Making Compound Metal Ingots; and I do hereby declare that the following is a full, clear, and exact description thereof, reference being had to the accompanying 10 drawings, forming a part of this specification, and in which—

Figure 1 represents a top or plan view of an apparatus for casting ingots composed of two or more grades of steel. Fig. 2 represents a 15 side view, partly in section, of the parts shown in Fig. 1. Figs. 3 and 4 are a side and bottom plan view, respectively, of a clamp device for holding the top of the hard bloom or core of the ingot in position in the mold, as 20 and for the purpose hereinafter described. Fig. 5 is a horizontal section on line *a*, Fig. 6, through part of the cast-iron bed and also part of the channeled fire-brick base embedded therein for conducting the molten metal 25 to the mold and upon which the bottom of the hard bloom or core principally rests, as will also be hereinafter described; and Fig. 6 is a vertical section through the parts shown in 30 Fig. 5 and through the bottom of the ingot-mold and said hard bloom or core, the same being a modification of the construction shown in Fig. 2.

My invention relates to what is commonly termed "bottom casting"—that is, castings 35 made by introducing the molten metal at the bottom of the ingot-molds and allowing it to flow upward therein; and it consists in combining with each mold and its hard bloom or core around which the molten metal flows a 40 fire-brick base of special construction and a top-clamp device for holding said hard bloom or core in position, as will be hereinafter more fully set forth.

To enable those skilled in the art to which 45 my invention appertains to better understand the nature and purpose thereof, I will now proceed to describe it more in detail with reference to the accompanying drawings.

In said drawings the parts marked A represent a number of ingot-molds grouped upon 50 a cast-iron bed B around a central vertical

conducting-pipe C, which is provided with a protecting-lining of refractory material D. Said central pipe and the ingot-molds rest principally upon a fire-brick base E, which is 55 recessed into the top of the aforesaid metal bed B, as is shown in Figs. 2, 5, and 6. Said fire-brick base is made in several sections and is provided with channels or ducts E', which radiate from the center to each ingot-mold, 60 the same connecting with the vertical opening of the conducting-pipe C and with each of the molds. The outer end of each channel terminates in a chamber E², which is preferably a little smaller in transverse diameter 65 than the size of the bottom of the opening in the mold, as is shown in Figs. 2 and 5, for the purpose hereinafter described. In said chamber E is formed a vertical base E³, projecting up from the bottom of the fire-brick to about 70 the level of the top surface of said fire-brick, upon which the hard bloom or core F, previously alluded to, is placed to support it in position vertically. An annular chamber is thus formed around said base E³ for the entering 75 molten metal to flow through and surround said hard bloom or core F as it passes up into the mold. By this construction said molten metal as it flows into the chamber E is distributed around the hard bloom or core and flows 80 upward in a uniform volume into the mold, thereby forming a casting of uniform texture and quality around said hard bloom or core, and in consequence a superior finished product. By thus first introducing the molten 85 metal into an annular chamber coming below the level of the mold and its hard bloom or core before entering said mold the latter and also the hard bloom or core are prevented from being eaten away by said molten metal 90 as rapidly as they otherwise would be if such provision were not made, and to facilitate the protection thus afforded said parts from the first intense heat of the molten metal the outer walls of the annular chamber E are 95 made to come a little inside of the wall of the mold, as previously described, and shown in the drawings. Therefore the molten metal in its upward motion does not at once directly strike said wall or inside surface of the mold, 100 and thereby in a measure protects the same. The hard bloom or core may be of any suit-

able size, shape, quality, or kind of metal suitable for producing the desired compound metal.

The hard bloom or core may be constructed 5 so as to rest in a slight depression formed in the top of the supporting-base E³, as is shown in Fig. 2, or its bottom end made to fit in a vertical opening in said base, as is shown in Figs. 5 and 6, or in any other suitable and 10 convenient manner.

A lining G of refractory material may be used upon the inside of the ingot-mold, as is shown in Fig. 6, or the same used without it, as preferred.

15 To facilitate the molten metal properly adhering to the hard bloom or core, the latter should be cleaned and heated before pouring the molten metal around the same.

The top of the hard bloom or core of each 20 mold is held in position laterally by means of a clamp device H, which is provided with downwardly-projecting lugs H' H', adapted to fit into the top of the mold, and with transverse screws H² H², which may be turned up 25 against the hard bloom or core when the clamp is fitted in position over the mold, as is shown in the drawings.

Having now described my invention, what I claim therein as new, and desire to secure by 30 Letters Patent, is—

1. In an apparatus for casting compound metal ingots, the combination of the ingot-molds, conducting-pipe, and metal bed with a fire-brick base fitted in said metal bed, hav-

ing radiating channels or ducts each terminating in a chamber under each ingot-mold, said fire-brick base having an upward-projecting support in each chamber for the hard bloom or core to foot upon; and the clamp device, adapted to fit over the top of the 40 mold and hard bloom or core, provided with downward-projecting lugs adapted to fit in the top of said mold and with set-screws adapted to be screwed against the hard bloom or core, substantially as and for the purpose 45 set forth.

2. In an apparatus for casting compound metal ingots, the combination of the ingot-mold and metal bed, with a fire-brick base fitted in said metal bed, having a chamber 50 under said mold and also provided with an upward-projecting support for the hard bloom or core to foot upon, substantially as and for the purpose set forth.

3. In an apparatus for casting compound metal ingots, the combination of the ingot-mold, with a clamp device for holding the top of the hard bloom or core in position laterally, said clamp device being provided with downward-projecting lugs adapted to fit into the top of the mold and with set-screws adapted to bear against the hard bloom or core, substantially as set forth.

JOHAN OTTO EMANUEL TROTZ.
